UNITED STATES PATENT OFFICE.

GEORGE S. MAXWELL, OF WASHINGTON, DISTRICT OF COLUMBIA, ASSIGNOR TO
A. RALPH SERVEN, TRUSTEE, OF WASHINGTON, DISTRICT OF COLUMBIA.

INTERNAL-COMBUSTION ENGINE.

1,253,023.

Specification of Letters Patent. Patented Jan. 15, 1918.

Application filed September 29, 1916. Serial No. 122,859.

To all whom it may concern:

Be it known that I, GEORGE S. MAXWELL, a citizen of the United States, residing at Washington, in the District of Columbia, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to internal combustion engines, and it has for its object to decrease the cost of fuel consumption in automobile or explosive engines.

To the accomplishment of the foregoing the invention contemplates the employment of a reservoir supplied with an explosive gas, which may be a fixed gas, or a volatile explosive substance or a combustible fluid or mixture, under pressure, a reservoir containing a suitable volatile combustible substance or mixture, and means operating under variations in pressure in one reservoir for supplying the compressed gas or material to the volatile combustible material to maintain a substantially constant or regulated pressure in the volatile combustible-material containing reservoir, so that an enriched gas or combustible mixture will be supplied as fuel as demanded for running the engine. The invention furthermore contemplates the employment, in connection with the foregoing, of means for supplying such enriched gas to the engine under variations in pressure within the air supply or intake pipe of the engine so that there will be an automatic supply of the enriched fuel to the engine; also to provide means for supplying volatile combustible material from its containing reservoir, in the event of failure of supply, in whole or in part, of compressed gas from its reservoir to the volatile combustible-material containing reservoir due to exhaustion of the gas in its reservoir, or to the failure or impairment of the automatic supply of the volatile combustible material from its reservoir to the engine, or from other causes; also to provide for the supply of gasoline or fuel to the carbureter in the usual way in the event of the failure of a supply of the enriched fuel, or of fuel

from the volatile combustible-material containing reservoir; and also to provide for the fuel being supplied from one or more of the sources of supply as desired.

To the accomplishment of the foregoing and such other objects as may hereinafter appear the invention consists in the features hereinafter particularly described and then sought to be clearly defined by the claims, reference being had to the accompanying drawings forming a part hereof, and in which—

Figure 1 is a side elevation with parts in section illustrating one embodiment of my invention;

Fig. 2 is a like view of one modification of the construction;

Fig. 3 a detail view illustrating pipe connections to and from the volatile combustible material containing reservoir.

In the drawings the numeral 1 designates a carbureter of any preferred well known construction or type; 2 the intake pipe to the carbureter; 3 the throttle; and 4, the manifold intake between the carbureter and explosive engine (not shown) all of which elements and their ordinary purpose and operation are well known and need no further description.

An auxiliary intake pipe 5 is provided which as illustrated in Fig. 1 may connect with the intake 2 between its throttle valve and carbureter or as illustrated in Fig. 2 may connect with the manifold intake 4 between the carbureter and the explosive engine (not shown). The auxiliary intake 5 communicates at one end with an air intake 6 and at the junction of the two pipes is a suitable valve 7 to control the port 8 between the pipes. This valve in the form selected for illustration is carried by a swinging arm 9 pivoted at 10 and under the influence of a compression spring 11 whose tension may be varied by an adjusting screw 12. The valve 7 is also designed to normally close the end of a pipe 13 leading from a reservoir 14 designed to contain a suitable volatile combustible material or mixture, for instance gasoline, which may be supplied to the reservoir through a cap 10 covered opening 15. This reservoir is in communication with a reservoir 16 in which is stored an explosive gas under compression, the gas being a fixed gas, or volatile explosive or combustible fluid or mixture 11.

and which is designed to enrich the volatile combustible material contained in the reservoir 14 so as to produce a highly efficient combustion fuel at the minimum or greatly reduced volume of consumption so as to very materially lessen the cost of running the engine. Between the two reservoirs, for instance in the piping or conduit 17 through which communication between the reservoirs is established, I place a suitable pressure regulating or reducing device for the purpose of maintaining a substantially uniform or constant pressure in the reservoir 14 whatever be the pressure or varying pressure in the storage reservoir 16. This pressure reducer or regulator comprises a shell or case 18 divided by a partition 19 into two compartments 20 and 21, the lower compartment or chamber being provided with an elastic or flexible diaphragm 22. The upper chamber or compartment 20 communicates by one branch of the pipe or conduit 17 with the compressed gas storage reservoir 16 and by the other branch of the conduit with the volatile combustible material reservoir 14, preferably below the combustible material contained therein, and the upper portion of the reservoir 14 is in communication through a pipe 23 with the chamber 21 of the pressure regulator 18 beneath the diaphragm 22. The gas receiving orifice 24 of the chamber 20 is opened or closed by a valve 25, preferably of the needle type, which works through the partition 19 and has its lower end resting upon a lever 26, the free end of which rests upon a stud 27 attached to the diaphragm 22, so that when the diaphragm is raised by a predetermined or excess of pressure in chamber 21 beneath the diaphragm the lever will be actuated so as to lift the valve and close the inlet orifice 24 so as to cut off the supply of compressed gas from reservoir 16 until the pressure in chamber 21 is reduced, whereupon the lever 26 and valve 25 will fall so as to open the inlet orifice 24 for the supply of additional compressed gas to the chamber 20 from which it will pass through pipe 17 to the reservoir 14 and through the combustible material contained therein so as to enrich the same. When the pressure in reservoir 14 reaches a predetermined degree the diaphragm 22 is forced upward so as to move the lever 26 and lift the valve 25 to cut off the supply of compressed gas from reservoir 16 until necessary to supply more gas from the reservoir which is determined by the reduction of pressure in reservoir 14 due to consumption of the volatile combustible material from reservoir 14. The chamber of the reducing device and associated parts will be so proportioned as to effect the operation described. While I have illustrated and described the preferred construction of parts for the purposes in view yet changes may be made therein without departing from the essential features for effecting the results sought. It is preferable that the pressure in reservoir 14 should be slightly above atmospheric pressure which will be maintained by valve 7 keeping closed the discharge end of pipe 13 by atmospheric pressure in the auxiliary intake plus the tension of spring 9. When however there is reduction of pressure in the auxiliary intake sufficient to overcome the resistance of spring 11 the valve 7 will be drawn away from the discharge end of pipe 13 and from the port 8, whereupon the enriched combustible gas from the reservoir 14 as well as air from the intake 6 will pass into the auxiliary intake 5 and from thence through either the intake 2 or the manifold intake 4, according to the form of construction used, and to the engine cylinder (not shown) and there be exploded in the usual way and for the usual purpose. When the suction in the auxiliary intake 5 created by the engine is reduced sufficiently the pressure of spring 11 will close the valve 7 and the supply of gas from reservoir 14 and air from intake 6 will be cut off until the variation of pressure in the auxiliary intake is again sufficient for the automatic opening of the valve for additional supply of explosive gas and air to the engine, and thus the operation is repeated in succession.

In the manner described an enriched combustible gas is furnished not only for starting but also for continuing the running of the engine, and without the necessity of using a carburetor as ordinarily practised. It also results in materially decreasing the cost of fuel consumption as the same volume of gasoline or volatile combustible material will last longer owing to the enriching of the volatile combustible material by the addition of the compressed fixed gas and the automatic supply of the enriched combustible fuel to the engine as well as the automatic supply of the compressed gas to the volatile combustible material in the storage reservoir in which a substantially uniform or constant pressure is maintained. The supply of the enriched explosive gas or mixture is not affected by weather conditions as the supply of the compressed gas to the volatile combustible material in the reservoir 14 obviates the necessity of a preliminary heating or warming of parts of the engine to obtain efficiency from the combustible or explosive fuel. When the supply of compressed gas in the reservoir 16 is exhausted, the reservoir may be detached and replaced by another charged reservoir for replenishing the supply.

In event of the pressure reducing valve between the reservoirs 14 and 16, or the auto-

- matic acting control valve 7, or both, should fail to operate to their normal efficiency, and it should be desirable to either supplement or to supplant their functions by bringing into action or play a carbureter, provision is made for such emergencies as follows. The reservoir 14 is connected by an emergency pipe or conduit 28 with the carbureter 1, and is provided with a cock 29 so that if it be opened the volatile combustible fluid in reservoir 14 may flow to the carbureter so that it may there be utilized in the customary way. This may be so whether it be supplemental to the enriched combustible fuel material passing through the auxiliary intake 5, or be the enriched combustible material alone passing from the reservoir 14 through the emergency pipe 28, or be the volatile combustible material supplied from the reservoir 14, with the supply of compressed gas from the reservoir 16 cut-off by means of the stop cock 30 provided for that purpose in the pipe or conduit 17 which effects communication between the reservoirs 16 and 14.
- 25 In addition to the foregoing there may be provided a tank or reservoir 31 for storing gasoline or other combustible fluid or mixture which may be supplied to the carbureter through a pipe 32 provided with a stop cock 33 for use in the ordinary way. It will thus be observed that in the event of the efficiency of any one of the methods of supply of fuel being impaired from any cause whatever it may be supplemented or 35 for the time being supplanted by one of the others, or if for any cause desirable, the fuel may be supplied at the same time from the several sources of supply. It will be understood that the several stop cocks may 40 be connected by any desired means with appropriate manipulating devices within convenient reach of the driver or operator as may be suggested by the skill of the mechanic and therefore not illustrated.
- 45 I have shown and described the necessary units and their connections and mode of operation with sufficient clearness to enable a person skilled in the art to practice the invention but it is to be understood that in the main features of the invention, I am not confined to the specific constructions illustrated although they are the preferred constructions.
- Having described my invention and set forth its merits what I claim is:
- 55 1. In internal combustion engines, the combination with means for conducting an explosive to the engine cylinder, of a reservoir for volatile combustible material, a reservoir containing under compression an enriching explosive agent, means effecting communication between the two reservoirs for enriching the contents of one by addition of the compressed explosive agent of the other, and means for mixing air and the enriched combustible fuel and conducting it to the point of explosion.
2. In internal combustion engines, the combination with means for conducting an explosive to the engine cylinder, of a reservoir for volatile combustible material, a reservoir containing under compression an enriching explosive agent, means effecting communication between the two reservoirs for enriching the contents of one by addition of the compressed explosive agent of the other, a pressure reducing device in communication with the two reservoirs for maintaining a substantially constant pressure in the reservoir containing the volatile combustible material. 75
3. In internal combustion engines, the combination with means for conducting an explosive to the engine cylinder, of a reservoir for volatile combustible material, a reservoir containing under compression an enriching explosive agent, means effecting communication between the two reservoirs for enriching the contents of one by addition of the compressed explosive agent of the other, and a pressure regulated device for controlling the flow of material from one reservoir into the other, said device operating under variations of pressure in one reservoir to cut-off or supply material from 90 one reservoir to the other. 85
4. In internal combustion engines, the combination with means for conducting an explosive to the engine cylinder, of a reservoir for volatile combustible material, a reservoir containing under compression an enriching explosive agent, means effecting communication between the two reservoirs for enriching the contents of one by addition of the compressed explosive agent of the other, and a pressure regulated device for controlling the cut-off and supply of material from one reservoir to the other, said device including a valve and a diaphragm 100 actuated by variation of pressure in one of the reservoirs for automatically cutting-off and supplying the material from one reservoir to the other. 105
5. In internal combustion engines, a reservoir for a volatile combustible material, a reservoir containing under compression an enriching explosive agent, means effecting communication between the two reservoirs for enriching the contents of one by addition of the compressed explosive agent of the other, an air-intake, an intake for the passage of combustible fuel to the explosive cylinder of the engine having a port communication with the air-intake, a conduit 120 for the volatile combustible material from its reservoir, and a valve controlling said port and the opening and closing of said conduit. 125
6. In internal combustion engines, a res- 130

ervoir for a volatile combustible material, a reservoir containing under compression an enriching explosive agent, means effecting communication between the two reservoirs 5 for enriching the contents of one by addition of the compressed explosive agent of the other, an intake for the passage of combustible fuel from the reservoir containing the volatile combustible material to the explosive cylinder of the engine, a carbureter, 10 and a valve controlled emergency conduit between the volatile combustible material

reservoir and the carbureter to supply material from the reservoir to the carbureter to supplement or supplant the supply of fuel by way of the intake from the reservoir.

In testimony whereof I affix my signature in presence of two witnesses.

GEORGE S. MAXWELL.
